CLAIM

The ornamental design for an electrical contact, as shown and described.

DESCRIPTION

FIG. 1 is a perspective view of the electrical contact.

FIG. 2 is another perspective view of the opposing side of the electrical contact in FIG. 1; and,

FIG. 3 is a top view of the opposing side of the electrical contact in FIG. 2.

The broken lines in the figures show portions of the electrical contact that form no part of the claimed design.

1 Claim, 3 Drawing Sheets

FIG. 1

FIG. 2

FIG. 3
